UNITED STATES PATENT OFFICE.

CHARLES J. FOX AND WALTER E. SCOTT, OF PROVIDENCE, RHODE ISLAND, ASSIGNEES
TO THE C. J. FOX COMPANY, A CORPORATION OF RHODE ISLAND.

DISPLAY DEVICE.

1,117,655.

Specification of Letters Patent. Patented Nov. 17, 1914.

Application filed March 28, 1914. Serial No. 828,050.

To all whom it may concern:

Be it known that we, CHARLES J. FOX and WALTER E. SCOTT, both citizens of the United States, residing at Providence, in the county of Providence and State of Rhode Island, have invented certain new and useful Improvements in Display Devices, of which the following is a specification.

Our invention relates to easel display cards for jewelry and has for its essential objects the provision of a means for displaying jewelry in a manner more conspicuous than that afforded by the ordinary flat jeweler's card; to render the article collapsible so as to occupy a minimum space in packing and transportation; and to attain these ends in a structure which is easy to manipulate, simple and inexpensive to construct, and which may be formed from a single blank.

To the above ends essentially our invention consists in such parts and combinations of parts as fall within the scope of the appended claim.

In the accompanying drawings which form a part of this specification, Figure 1 is a plan view of a blank from which our display card is ultimately formed, Figs. 2, 3, and 4, front, side, and rear elevations respectively of our easel card, and Fig. 5, a section on line $x-x$, of Fig. 2.

Like reference characters indicate like parts throughout the views.

Our card or rack is formed from an oblong blank of thin cardboard A, cut out with oppositely disposed pointed projections a at an intermediate point in its length. Spaced from the projections a and somewhat nearer the opposite end of the blank are oppositely disposed pointed projections b. Near one end of the blank or strip A is a longitudinal opening C formed by cutting from the body of the blank a rectangular portion c which is left attached to the strip itself at the end of the opening a as at d. Centrally disposed in the blank intermediate the points a is an arched arcuate slit D; while near the end of the blank opposite that containing the flap c

is a small arcuate slit E, forming a flap e located in alinement with said flap. This blank has a transverse bend intermediate the points d as at E, and a transverse bend F extending from the points a to the ends of a slit D. A further transverse bend G extends across the strip at the end of the bend C. Located one above the other in the center of the blank are curved transversely disposed slits h. From this strip our display rack is easily formed by bending the parts at the lines E, F, and G as indicated. The portion I of the blank between the bends E and F forms the body or face of the device; the lower end portion J of the blank forms the base; the portion K between the bends F and G forms the leg; and the upper end portion L forms a foot adapted to slide intermediate the base J and the flap e. The tongue C forms a brace adapted to bear against the body I, and maintain the foot I in position beneath the flap e.

Beneath the flaps m formed by the slits h respectively may be placed the shoes of collar buttons, or the portions of the article sought to be displayed upon the device. In case where the article to be attached has a pin attachment, such as a brooch, or has a back not particularly adapted for engagement in the slits h it will be understood that the slits or openings h may be circular and may have substituted therefor slits h² of circular shape or other shape.

What we claim is,—

In a jewelry display device, the combination of a body, a rearwardly directed base integral with the body, a flap upon the base, a leg integral with the body, a foot upon the leg beneath the flap, and a brace upon the leg adapted to bear against the body.

In testimony whereof we have affixed our signatures in presence of two witnesses.

CHARLES J. FOX.
WALTER E. SCOTT.
